CLAIM

The ornamental design for a firearm rail, as shown and described.

DESCRIPTION

FIG. 1 is a bottom, rear, left side perspective view of a firearm rail according to the present disclosure;

FIG. 2 is a right side view of the firearm rail of FIG. 1;

FIG. 3 is a left side view of the firearm rail of FIG. 1;

FIG. 4 is a top view of the firearm rail of FIG. 1; and,

FIG. 5 is a bottom view of the firearm rail of FIG. 1.

The broken lines in the Figures represent portions of the

firearm rail that form no part of the claimed design.
